UNITED STATES PATENT OFFICE

142,577

DESIGN FOR A CONTAINER FOR WATER TREATING MATERIAL

Clarence H. Morrow, Shaker Heights, Ohio, assignor to The Hotstream Heater Company, Cleveland, Ohio, a corporation of Ohio

Application April 7, 1945, Serial No. 118,889

Term of patent 14 years

(Cl. D16—2)

To all whom it may concern:

Be it known that I, Clarence H. Morrow, a citizen of the United States and a resident of Shaker Heights, in the county of Cuyahoga and State of Ohio, have invented a new, original, and ornamental Design for a Container for Water Treating Material, of which the following is a specification, reference being had to the accompanying drawing, forming a part thereof.

In said drawing, Fig. 1 is a side elevational view of a container for water treating material showing my new design; Fig. 2 is a top plan view of such container; and Fig. 3 is a bottom plan view of such container.

I claim:

The ornamental design for a container for water treating material, as shown.

CLARENCE H. MORROW.
